UNITED STATES PATENT OFFICE.

JOHN S. YARD, OF TRENTON, ASSIGNOR TO THE MOORE BROTHERS COMPANY, OF ELIZABETH, NEW JERSEY.

DESIGN FOR A RADIATOR.

SPECIFICATION forming part of Design No. 25,045, dated January 7, 1896.

Application filed November 3, 1894. Serial No. 527,843. Term of patent 7 years.

To all whom it may concern:

Be it known that I, JOHN S. YARD, a citizen of the United States, residing at Trenton, Mercer county, New Jersey, have invented a new and original Design for Radiators, fully described and represented in the following specification and the accompanying drawings, forming a part of the same.

This design relates to a specific ornamental form and configuration for embodiment in that type of radiators composed of a connected series of upright loops or sections; and it consists in the particular features of ornamentation of the individual loops or sections herein shown and described.

In the annexed drawings, Figure 1 is an end elevation of a radiator formed of upright sections embodying my design, and Fig. 2 is an edge view of one of the end loops or sections.

Each loop comprises the two upright columns A, connected together at the top by a convexly-arched transverse member B having the upwardly-projecting and divergent horns D, and similarly at the bottom by the transverse member C, constituting the base and forming with the other members a substantially O-shaped structure. The base is shown formed with the central annular hub E having its lower side depending therefrom, and with a smaller hub F above the same. The base is provided also with the divergent feet G formed with concave outer edges, the junction of which with the outer edges of the columns A is intercepted by the lateral convex projections C'.

Upon the face of each column and the head B is a continuous rib or bead I extending parallel with the outer edges and dying away tangentially at the base in a transverse line of the foliated pattern of its surface ornamentation, such rib inclosing a smooth and undecorated panel a extending continuously around the adjacent sides of the columns and their upper and lower connecting members. Those portions of the surface of the section lying outside of the rib or bead I are subdivided by the vertical bead J extending along the outer edge of each column from the projection C' upwardly to a point a little below the horn D, where it terminates at a series of

scale-like projections occupying the intervening space and extending laterally somewhat beyond the line of the said rib or bead. Both faces of the head of the section are decorated in the outer panels with two acanthus-leaves covering the surface of the same and that of the horns D, into which they extend, their stems b being bent into spiral form and placed in juxtaposition to form a conventional scroll 60 at the center. Chains of leaves d, extending from the same stems, are draped over a short distance down the columns A, the patterns thus formed diminishing in density as they recede from the scroll.

The base is provided upon opposite sides of the hub F with foliated scrolls e connected together above such hub by the stems of the two leaves forming such scrolls, and a chain of acanthus-leaves d similar to those at the top of the column is extended upwardly upon the latter a short distance, the stems of their principal leaves forming offshoots from the body of such scrolls.

Each of the feet G is provided upon its outer edge with a vertical rib G' dividing its surface into two portions, both of which are decorated with a conventional pattern g, comprising a reflexed stem having an acanthus-leaf at each end and wholly occupying the space between the scroll e and the outer line of the section upon the base. The foliated patterns at the two ends of the section are connected together upon the intervening smooth background by the tapes or ribbons e, the one originating in the scroll b and represented as draped over the leafwork d in a wavy line to about the middle of the column and terminating in the forked ends lying across the panel, and the other extending upward from the lower foliated pattern and represented as issuing from underneath the principal leaf d of the pattern and similarly draped upon the column to a point a little beyond the end of the other and intertwined therewith.

The essential feature of the design is the particular shape of the radiator-section combined with the special pattern of ornamentation therefor illustrated in the drawings.

I am aware that it is not new in itself to interrupt the curvature of the head of a ra-

diator-loop of this class by horns or projections thereon, nor to vary the degree of ornamentation upon the columns from the ends toward the middle in a foliated pattern applied thereto, nor to divide the surface of a radiator-loop into distinct panels by means of vertical ribs upon the faces and outer edges of its columns, which features of the present design are disclosed in the United States Patents No. 18,440, of July 10, 1888, No. 21,234, of December 15, 1891, and No. 22,787, of September 12, 1893, and I do not therefore claim such features herein as individually new. I am not aware, however, that a radiator-loop has ever been provided with the particular details of form, nor with the specific foliated patterns for the head and base of the structure and the intertwined

connecting tapes or ribbons shown and described herein, which impart to the radiator a novel and distinctive appearance from those produced by the prior designs referred to above, and I therefore disclaim the latter, limiting myself to the specific design described and illustrated herein.

What I claim herein is—

The design for a radiator herein shown and described.

In testimony whereof I have hereunto set my hand in the presence of two subscribing witnesses.

JOHN S. YARD.
